UNITED STATES PATENT OFFICE.

MILTON E. CAMPANY, OF HAMILTON, ASSIGNOR OF ONE-HALF TO HORACE B. PECK, OF KALAMAZOO, MICHIGAN.

EXTENSIBLE CAR-STEP.

SPECIFICATION forming part of Letters Patent No. 436,454, dated September 16, 1890.

Application filed July 9, 1890. Serial No. 358,188. (No model.)

To all whom it may concern:

Be it known that I, MILTON E. CAMPANY, a citizen of the United States, residing at Hamilton, in the county of Allegan and State of Michigan, have invented certain new and useful Improvements in Extensible Car-Steps; and I do hereby declare the following to be a full, clear, and exact description of the invention, such as will enable others skilled in the art to which it appertains to make and use the same.

My invention relates to an extensible car-step for railroad-cars, which is adapted to fold out of the way when the car is in motion and to be let down in position for use when the car stops, and that is under the control of and may be operated from the locomotive; and it consists in the construction, combination, and arrangement of the various parts hereinafter described, and pointed out in the claims, reference being had to the accompanying drawings, wherein—

Figure 1 is a side elevation with parts broken away to show details of a device embodying my invention; Fig. 2, a rear elevation of the same, and Fig. 3 a detail in plan of the locking mechanism.

Like letters of reference indicate like parts in each of the figures.

A represents the platform of an ordinary railway-car, to which is secured the ordinary permanent railway-car steps C, having side boards B.

C' represents an extensible step, which is pivoted between the inwardly-turned ends of the pendent arms D' D' of the transverse bar D, journaled underneath the lower step C in such a manner that when the bar D is turned so as to fold the arms D' D' underneath and parallel to the lower step the step C' will be folded underneath the same, as shown in Fig. 1 by dotted line.

E represents a guide-bar provided with a slot P at its upper end, and having a forwardly-projecting portion E' at an angle with the main portion and engaging with and secured to the under side of the step C' for operating the same, and has its upper end corner beveled to form a shoulder for engaging the angle-plate O, secured to the under side of one of the steps for locking and holding the step C' rigid.

G is a transverse rock-shaft journaled at the angle of the riser and tread of the upper step, and has the pendent crank-arm F, engaging the slot P at its lower end, and has the crank-arins H H', secured to its end outside the side board B and underneath the timber A. To the outer end of arm H is attached the hand-rod K, for operating the device by hand when the air-cylinder is not employed.

L represents a spring-latch arranged on the top of the platform, which engages with a notch in the side of rod K to lock it in its upper position when the step is down, and M represents an eccentric to hold the latch from engagement. The end of the lever H' engages with the end of the piston-rod I of the air-cylinder J, for operating the step by air-pressure from the locomotive.

N is a retracting-spring, having one end attached to the platform and the other to the arm F, for retracting the same when the air-pressure is removed.

Air is forced into the cylinder J through the pipe J' from the air-tank on the engine in the usual manner, causing the piston I to be thrust downward, depressing arm H', and thereby producing a partial revolution of G, actuating F and E, and extending C', as shown in the drawings. The forward impulse of E is such as to throw its upper end into engagement with O, thereby locking firmly, holding the step. Pressure upon C' holds it firmer, as will be readily comprehended. When the air-pressure is removed the spring N retracts the arm F and draws the step back into its former position. The car being disconnected from the engine, the step may be operated by the hand-rod K and latch L, as is obvious.

What I claim is—

1. The herein-described extensible car-step, comprising the bar D, journaled on the permanent steps, having the pendent arms D' D', and the step C', pivoted between said pendent arms, a transverse rock-shaft G, journaled on the permanent steps, having crank-arms, and a bar E, connecting one of said crank-arms to said step and having limited play thereon, substantially as herein set forth.
2. The herein-described extensible step, comprising the folding step C', hung by parallel pendent arms D' D' from the permanent

steps, a transverse rock-shaft G, journaled on the permanent steps, having a crank-arm F, arranged in the rear of the step, and a bar E, having one end connected with the step and the other end formed with an elongated slot P, to receive the lower end of said crank-arm, substantially as set forth.

3. The combination, with the permanent steps, of an extensible step C', pivoted between the pendent arms D'D', as set forth, a rock-shaft G, having a crank-arm F, and a rod E, having the portion E' at an angle to the main portion secured to the step and connecting the arm F and step, the lever connected with the rock-shaft, the latch, and the eccentric engaging the latch, substantially as set forth.

4. The combination, with the permanent steps, of an extensible step C', pivoted between the pendent arms D'D', as set forth, a bar E, having the portion E' at an angle to the main portion of the bar, the plate O, se-

cured to the permanent steps and engaging the upper end of the bar E, and means of lifting the bar E, a spring-latch to engage the operating-lever, and the eccentric engaging the latch, substantially as described, and for the purposes set forth.

5. The combination, with the permanent car-steps, of the extensible step C', pivoted between the pendent arms, as set forth, the bar E, having the portion E' secured to the step, the transverse rock-shaft G, journaled on the permanent steps, having the crank-arm F, attached to the bar E, and the crank-arm H on the rock-shaft and connected to the air-cylinder J, substantially as described, and for the purposes set forth.

In testimony whereof I affix my signature in presence of two witnesses.

MILTON E. CAMPANY.
